Statement Regarding Potential Prior Art Submitted on Nov. 18, 2014 from U.S. Appl. No. 13/769,517.

Primary Examiner — Mark A Goodwin(74) *Attorney, Agent, or Firm* — Calfee, Halter & Griswold LLP(57) **CLAIM**

We claim the ornamental design for a plow blade damping member, as shown and described.

DESCRIPTION

FIG. 1 is a perspective view of an embodiment of a plow blade damping member of the new design;

FIG. 2 is a front view of the plow blade damping member of FIG. 1;

FIG. 3 is a rear view of the plow blade damping member of FIG. 1;

FIG. 4 is a right side view of the plow blade damping member of FIG. 1;

FIG. 5 is a left side view of the plow blade damping member of FIG. 1;

FIG. 6 is a top view of the plow blade damping member of FIG. 1; and,

FIG. 7 is a bottom view of the plow blade damping member of FIG. 1.

The portions of the Figures shown in broken lines are for illustrative purpose only and form no part of the claimed design.
